UNITED STATES PATENT OFFICE.

SAMUEL D. BRIGHTMAN, OF NEW YORK, N. Y.

DESIGN FOR LEATHER.

40,843.

Specification for Design. Patented Aug. 30, 1910.

Application filed June 1, 1910. Serial No. 564,531. Term of patent 3½ years.

To all whom it may concern:

Be it known that I, SAMUEL D. BRIGHTMAN, a citizen of the United States, residing in the city of New York, borough of Brooklyn, in the county of Kings and State of New York, have invented a new, original, and ornamental Design for Leather, of which the following is a specification, reference being had to the accompanying drawing, forming a part thereof.

The figure is a view of the face of a strip of leather showing my new design.

I claim:

The ornamental design for leather as shown.

SAMUEL D. BRIGHTMAN.
